UNITED STATES PATENT OFFICE

155,115

DESIGN FOR A TOY ANIMAL FIGURE

Constance Woods, Mercer, Pa., assignor to Baby-Safe Toys, Inc., Mercer, Pa., a corporation of Pennsylvania

Application January 10, 1948, Serial No. 143,660

Term of patent 7 years

(Cl. D34—2)

To all whom it may concern:

Be it known that I, Constance Woods, a citizen of the United States, residing at Mercer, in the county of Mercer and State of Pennsylvania, have invented a new, original, and ornamental Design for a Toy Animal Figure, of which the following is a specification, reference being had to the accompanying drawings, forming part thereof.

I claim:

The ornamental design for a toy animal figure, substantially as shown.

CONSTANCE WOODS.
